UNITED STATES PATENT OFFICE

ERNEST F. MANN, OF MOUNT HOPE, WEST VIRGINIA

DESIGN FOR A DIRECTION-SIGNAL CASING

Application filed January 15, 1930. Serial No. 34,133. Term of patent 7 years.

To all whom it may concern:

Be it known that I, ERNEST F. MANN, a citizen of the United States of America, residing at Mount Hope, in the county of Fayette and State of West Virginia, have invented a new, original, and ornamental Design for a Direction-Signal Casing, of which the following is a specification, reference being had to the accompanying drawing, forming a part hereof.

In the drawing:

Figure 1 is a front elevation of a direction signal casing showing my design.

Figure 2 is a top plan view of the same.

I claim:

The ornamental design for a direction signal casing, as shown.
